UNITED STATES PATENT OFFICE.

DAVID H. BLASCOW, OF NEW YORK, N. Y., ASSIGNOR TO PETER GARRAHAN
AND FRANCIS M. NEALE, OF SAME PLACE.

REIN-HOLDER.

SPECIFICATION forming part of Letters Patent No. 553,219, dated January 14, 1896.

Application filed May 15, 1895. Serial No. 549,408. (No model.)

To all whom it may concern:

Be it known that I, DAVID H. BLASCOW, a citizen of the United States, residing in the city, county, and State of New York, have 5 invented certain new and useful Improvements in Rein-Holders, of which the following is a specification.

My invention relates to the class of rein-holders wherein the holder is adapted to be 10 clamped to the top of the dashboard and is provided with a rocking cam to clamp on the reins when they are inserted in the bite of the holder, and the main object of the invention is to provide the holder with a gravity 15 detent or latch which will prevent the reins from being drawn out laterally from the holder by the movements of the horse, and to provide a construction which will permit the driver to remove the reins from the holder 20 with one hand, the latch being lifted through the medium of the reins, as will be described. The holder is capable of being secured to the dashboard at any point along its upper edge, and without marring or perforating the 25 leather of the dashboard.

The novel features of the invention will be defined in the claims.

Figure 1 is a side elevation of a holder embodying the invention. This view represents 30 the right-hand side of the holder mounted on the dashboard, which is represented in vertical section. Fig. 2 is a rear elevation of the holder—that is, a view of the face next to the driver. Fig. 3 is a side elevation of the holder, 35 showing the side seen in Fig. 1, but with the cam and latch lifted in order to permit the reins to be removed. Fig. 4 is a vertical sectional view of the holder. This view shows the holder secured to a dashboard, which 40 differs slightly from that seen in Figs. 1 and 2.

X represents part of an ordinary dashboard such as may be found on any carriage. The form of dashboard shown in Fig. 4 has a metal bar above the bar inclosed in the leather.

45 Both forms shown are common.

The rein-holder has a main base-piece, comprising two jaws *a* and *b*, between which the dashboard is embraced, the jaw *a* having set in it one or more clamp-screws *c*, which pass 50 through the jaw and set on a protecting-piece *d*, of leather or the like, interposed between

the screws and the leather of the dashboard. Another similar piece *d'* is arranged between the jaw *b* and the other face of the dashboard. The upper part of the base-piece 55 consists of a frame *e* in somewhat the form of the letter L inverted. In this frame is hung a gravity-cam *g*, arranged to swing or rock on a rod or bar *h*, in the upper part of the frame. This cam has a convex or rounded serrated 60 face *g'*, which is eccentric to the rod *h* and is hollowed out at *x*, Fig. 4, and left solid and heavy at *x'*, so that the cam will hang in the position seen in Figs. 1 and 4. The construction of the frame *e* provides an opening *y* at 65 one side, as seen in Fig. 2, whereat the reins *Y* are inserted under the cam *g* by a lateral or sidewise movement. The cam is so set in the frame that when the horse pulls on the reins gripped in the holder the strain serves 70 to rotate the cam and tighten its grip on them. The side of the holder at the right in Fig. 1 is that toward the horse.

To prevent the horse, by any jerking movement of his head, from slipping the reins out 75 laterally from under the cam, a gravity detent or latch *i* is hung from the rod *h*, its pend- 80 ent end just clearing the table *j* of the base-piece on which the reins rest. This latch is capable of swinging toward the driver— 85 that is, to the left, as seen in Figs. 1 and 3. On the cam *g* is a stud or pin *k*, which, when the reins are drawn back in a manner to swing or rock the cam, catches the latch and swings it back and up, as illustrated in Fig. 85 3, so as to permit the reins to be moved or drawn out under the latch by a quick lateral movement, as indicated in Fig. 3. When the reins are removed the latch and cam return by gravity to their normal positions. 90

The latch is made bulbous at its lower end and beveled at *i'*, Fig. 2, on its outer face, so as to facilitate the passing of the reins under it and swinging it back.

In order to avoid rattling and clanking of 95 the metal parts when shaken by the movements of the carriage, I provide the cam *g* with a cushion *m*, of rubber or like soft material, to contact with the top of the frame *e*, and furnish the stud *k* with a similar cushion 100 *n*, Fig. 1, to contact with the latch *i*. Bosses on the latch *i* and cam *g* prevent them from

clicking together or against the frame of the holder.

In some cases the dashboard of a vehicle may not be adapted to receive the clamp of the holder, in which the holder may be clamped to any other convenient part of the carriage. Indeed, the clamp may be shaped to fit any part of the vehicle.

Having thus described my invention, I claim—

1. In a rein-holder, the combination with a frame provided with a clamp for clamping it on the vehicle, of a serrated gravity cam; *g*, suspended in the upper part of the frame, and a gravity latch *i*, suspended in the frame across the opening for the insertion of the

reins under the cam, the cam *g* having a stud *k*, for displacing the latch, substantially as set forth.

2. In a rein-holder, the combination with the frame *e*, of the cam *g*, suspended therein and provided with a cushion, *m*, and a cushioned stud *k*, and the latch suspended across the opening in the frame whereat the reins are inserted, substantially as set forth. 25

In witness whereof I have hereunto signed my name in the presence of two subscribing witnesses.

DAVID H. BLASCOW.

Witnesses:

HENRY CONNETT,
JAS. KING DUFFY.
